W.C. BRUSON.

Sugar Press.

No 87,090.

Patented Feb. 23, 1869.

WILLARD C. BRUSON, OF CHICAGO, ILLINOIS.

Letters Patent No. 87,090, dated February 23, 1869.

IMPROVEMENT IN SUGAR-PRESSES.

The Schedule referred to in these Letters Patent and making part of the same.

To all whom it may concern:

Be it known that I, WILLARD C. BRUSON, of the city of Chicago, in the county of Cook, and State of Illinois, have invented a new and improved Sugar-Press; and I do hereby declare that the following is a full, clear, and exact description of the construction and operation of the same, reference being had to the accompanying drawings, and letters of reference marked thereon, making a part of this specification, in which—

Figure 1 is a perspective representation of my new and improved sugar-press, the plane of longitudinal section being indicated by the line 2 2.

Figure 2 is a vertical central sectional elevation of the same.

Figure 3 is a perspective representation of the core-cylinder.

Figure 4 is a perspective representation of the lower and the inverted perforated conical top.

Figure 5 is a top view of the follower, shown at fig. 4, with the conical plate removed.

Figure 6 is a view of the lower end of the core-cylinder.

Figure 7 is a transverse section of the fall-leaf conductor; also, an elevation of the buttons, and a broken section of the iron frame A.

Figure 8 is a plan view of the stationary and fall-leaf conductors.

The object of my invention is to provide a powerful and convenient press, by the use of which the molasses can be speedily forced out of mush-sugar, which term is commonly applied to partially crystallized or granulated sorghum, imphee, muscovado, beet, maple, and all kinds of undrained sugar.

It is well known among experienced sorghum-sugar growers, that sorghum-sirup contains more or less vegetable albumen, which is a gummy, waxy, substance, and when the sirup crystallizes, the gummy substance remains incorporated in the mush-sugar, and prevents it from draining, or the molasses from being forced out, by means of the ordinary presses, with the rapidity necessary to make the business profitable.

The common slotted or perforated pressing-boxes which are now in use, either with or without fine cloth, secured either outside or inside of the press-box, separate but a small proportion of the molasses contained in the mush-sugar, as the gummy substance adheres to the cloth in a very brief time, which prevents the escape of the molasses, thus rendering the means heretofore used practically useless.

Furthermore, the requisite pressure for separating the molasses from the mush-sugar, by means of the ordinary presses, has a tendency to force about one-half of the molasses to the central part of the press-box, and there the liquid remains, which again effectually defeats the separation desired.

In my invention, I claim to have obviated what has

heretofore been the principal objection, as above mentioned, by not only giving a free external passage for the molasses, but forming a complete central drainage in the press-box, hoop, or cylinder, by which device a speedy and effectual separation of liquids from all kinds of solids may be produced.

To enable others skilled in the art to make and use my invention, I will proceed to describe its construction and operation, by referring to the above-mentioned drawings, and letters of reference marked thereon.

A represents the strong and substantial frame, made of iron or other suitable material, upon which rests the platform B, and underneath this platform is attached the stationary conductor N, in which is made the spout or groove D', extending about one-fourth the length of the platform B.

The conductor N is firmly secured to the frame A.

At O is shown the fall-leaf conductor, with the necessary grooves, C and A', one end being annexed to the conductor N, and hung to the frame A, by means of hinges, or other suitable fastenings.

The other end of the conductor O is held in its proper position, which is about horizontal when in use, by one or more buttons P, which can be turned so as to allow the end of the conductor to fall downward to a vertical position, as shown by the dotted line J', fig. 2, when it is desired to discharge the contents of the press-box Q R.

This press-box is made of two perforated metallic plates, the inside plate R being perforated with holes small enough to prevent the escape of grained sugar, and, at the same time, allow a free escape of molasses.

The outside plate Q contains larger perforations, and is used to prevent the inside plate from being strained by pressure.

They are joined together at the top and bottom by rivets, solder, or otherwise, thus forming a double cylinder, the bottom of which rests on the rabbet K', for the purpose of having a permanent rest or seat, that the same may stay in its place.

The platform B has a central opening, as shown at fig. 2, equal to the inside diameter of the cylinder Q R, for the purpose of allowing the solid contents of the cylinder Q R to be discharged.

At C is shown the rim, elevated above the platform B, terminating in the spout B', used for conducting the molasses pressed out of the cylinder Q R into the receiving-pan L, which stands immediately in front of the press.

Y represents the follower, the form of the top being an inverted cone, and containing the grooves n n, as shown at fig. 5, terminating in the opening I', which extends vertically through the follower Y.

The grooves n n are covered with one or more thicknesses of perforated metallic plate, as shown at U, fig. 4, for the purpose of allowing a free escape of molasses.

X represents the cylindrical rim, attached to the centre of the metallic plate U, and is used to support the core-cylinder S, which stands vertically over the centre of the follower Y.

When in use, this cylinder is secured to the rim X by means of the rod W, and catches I, to prevent its being displaced.

The cylinder S is constructed of the same kind of metallic plates as the cylinder Q R, and the finer-perforated plate is placed upon the outside of the plate containing the larger perforations, which is necessary, because the pressure on the core-cylinder S is inward.

Surrounding the follower Y is the collar Z, composed of India rubber, leather, or other suitable material, used for the purpose of preventing the mush-sugar from escaping between the follower and the inner surface of the cylinder Q R.

When in use, the follower Y is placed in the bottom of the cylinder Q R, and rests upon the fall-leaf conductor O, at which time this conductor is secured in a horizontal position by means of the buttons P.

F' shows the follower made of rubber, leather, or other suitable material, which is designed to be used on the top of the mush-sugar in the cylinder Q R, and has an opening in the centre for the purpose of passing over and fitting closely to the outside of the core-cylinder S, and the inside surface of the cylinder Q R, for the purpose of preventing the escape of the contents of the cylinder upward, when subject to a pressure.

At G is shown the plunger, in which is made the air-chamber G', which passes over the outside of the core-cylinder S.

The flange L', on the lower part of the plunger, extends from the air-chamber to the inside surface of the cylinder Q R, and, when in operation, rests on the upper surface of the follower F', for the purpose of forcing downward the contents of the cylinder Q R.

D represents the standards, in which are cut the slots E, for the purpose of guiding the arms F, which are attached to the upper part of the plunger G, and forced down by means of the shaft I and rope or chain H, attached to the arms F' and shaft I, on each side of the press, which shaft I passes through horizontal bearings in the frame A, and to the upper portion of this frame is firmly attached the lower part of the standards D.

At J is shown the common lever and ratchet-wheel K, by means of which the shaft I is operated.

The weight & is hung on the opposite end of the lever, for the purpose of securing an even and steady pressure.

E' represents the platform, to which the press is attached for convenience and use.

Operation.

In order to use my invention, it is necessary to place the follower Y and core-cylinder S in the cylinder Q R, as shown in fig. 2.

The cylinder Q R may then be filled with any quantity of mush-sugar, or other substance to be pressed, not to exceed the red line 3 3.

The follower F must then be placed upon the top of the core-cylinder S, and pressed down upon the mush-sugar; then place the flange L', of the plunger G, on the follower F', which will allow the core-cylinder S to enter the air-chamber G'.

It will be seen, from this description, that in forcing the plunger G downward by means of the lever J, as above-described, the molasses contained in the mush-sugar will be driven through the perforations in the cylinder Q R, and conveyed, by the rim C, through the spout B', into the receiving-pan L. At the same time the molasses in the central portion of the cylinder Q R will be pressed through the perforations of the core-cylinder S, and pass out through the grooves n n and the opening in the follower Y, and conveyed, by the grooves upon the conductors O N, into the receiving-pan L.

The air contained in the chamber G' furnishes the required pressure to prevent the grooves n n from clogging, and forces the molasses entirely clear from the inside of the core-cylinder S.

When the molasses has been pressed out of the sugar, the fall-leaf conductor O may be let down by turning the buttons P, as shown by the dotted lines J', which will permit the sugar in the cylinder Q R to pass into the sugar-receiver M, which sets directly under the opening in the platform B, and the operation is completed.

Having thus described my invention,

I claim as new, and desire to secure by Letters Patent—

1. The follower Y, supporting the conical perforated plate U and the core-cylinder S, constructed and arranged to operate in the manner substantially as set forth.

2. The general arrangement of the cylinders Q R, conductors O N, follower Y, core-cylinder S, and air-chamber G', constructed to operate substantially as specified.

WILLARD C. BRUSON.
